T. FARMER, JR.
DOOR MOTOR.
APPLICATION FILED AUG. 16, 1915.

1,262,934.

Patented Apr. 16, 1918.

Thomas Farmer Jr., Inventor

By his Attorney

E. L. Bentley

UNITED STATES PATENT OFFICE.

THOMAS FARMER, JR., OF NEW YORK, N. Y., ASSIGNOR TO CONSOLIDATED CAR-HEATING COMPANY, OF ALBANY, NEW YORK, A CORPORATION OF WEST VIRGINIA.

DOOR-MOTOR.

1,262,934.

Specification of Letters Patent. Patented Apr. 16, 1918.

Application filed August 16, 1915. Serial No. 45,665.

To all whom it may concern:

Be it known that I, THOMAS FARMER, Jr., a citizen of the United States, residing at New York city, borough of Manhattan, 5 county and State of New York, have invented certain new and useful Improvements in Door-Motors, the following being a full, clear, and exact disclosure of the one form of my invention which I at present 10 deem preferable.

For a detailed description of the present form of my invention, reference may be had to the following specification and to the accompanying drawings, which illustrate my 15 invention.

My invention relates to the control of pneumatic motors employed to operate doors. In brief I provide that a latch which serves to lock the door shall be also made to control the duration of action of the motor. 20

In the accompanying drawing, A represents a door and B a pneumatic motor of any desired construction which serves to open and close the door. The motor is controlled, for door-opening, by a valve V' operated by a magnet M' and, for door-closing, 25 by a valve V² operated by a magnet M². C is a latch engaging a notch in the upper edge of the door and locking the door in 30 closed position, as shown in the figure. D is a cylinder supplied with air pressure by the pipe d whenever air is admitted by valve V' to the motor B to open the door. A piston in cylinder D lifts the latch C to unlock the door just prior to its opening. When the latch is lifted and the door starts, 35 the latch will ride on the upper edge of the door while the door is moving and will drop off the front corner of the door when its opening movement is completed. While the latch is thus lifted it will close the two contacts c', c² and thereby close a shunt around each of the two push-button switches m' and m² which control the respective valves- 40

magnets M' and M². Thus, to start the opening of the door, the switch m' of magnet M' will be closed momentarily by the operator. That will admit air to the right-hand end of the motor (also to the latch-lifting cylinder D) and the motor will start 45 to open the door. The circuit of valve-magnet M' will be kept closed at c' by the retaining circuit shunting switch m' until the door has completed its run when the 50 latch will drop off the corner of the door 55

and open the retaining circuit at c'. To close the door, the switch m² will be momentarily closed by the operator, causing magnet M² to open valve V² and admit air pressure to the left-hand end of the motor 60 B. When the door starts it will lift the latch, thereby closing the retaining circuit of magnet M² at the contacts c², and that retaining circuit will remain closed until the door has made its run and the latch 65 drops into its locking notch. The battery will be connected by the switch E to the two magnet circuits alternately when the motor reaches the end of its stroke, said switch having projections positioned to be engaged 70 by a projection on the piston of the motor. It will be understood that said switch E is merely illustrated diagrammatically in the drawing, and that suitable means such as a spring catch E' is provided to hold it to 75 either of its circuit closing positions. The valves V' and V² are ordinary two-way valves, normally connecting both motor cylinders to exhaust, but acting, when operated by their magnets, to shut off the exhaust and 80 open the supply.

What I claim as new and desire to secure by Letters Patent is:

1. The combination with a door and a pneumatic motor for operating the same, of 85 a valve controlling said motor, a lock for the door, means controlled independently of the lock for opening said valve, and means controlled by the lock for causing said valve opening means to maintain said valve in 90 open position until the door reaches the end of its movement.

2. The combination with a door and a pneumatic motor for operating the same, an electrically actuated valve for controlling 95 said motor, a lock for the door, a starting circuit for opening the valve, and a maintaining circuit for said valve controlled by said lock.

3. The combination with a door and a 100 pneumatic motor for operating the same, of a valve controlling said motor, a lock for the door, means controlled independently of the lock for opening said valve, means controlled by the lock for causing said valve 105 opening means to maintain said valve in open position until the door reaches the end of its movement, and means operable upon the opening of said valve for moving said lock. 110

4. The combination with a door and a pneumatic motor for operating the same, of a valve controlling said motor, a lock for the door, means controlled independently of the lock for opening said valve, means controlled by the lock for causing said valve opening means to maintain said valve in open position until the door reaches the end of its movement, and pneumatic means controlled by the valve for operating said lock. 80
5. The combination with a door and a pneumatic motor for operating the same, an electrically actuated valve for controlling said motor, a lock for the door, a starting circuit for opening the valve, said circuit including a starting switch, a maintaining circuit shunting said switch, and a switch operated by said lock for controlling said maintaining circuit. 85
6. The combination with a door and a pneumatic motor for operating the same, of an opening valve for said motor, a closing valve for the motor, a lock for the door, means controlled independently of the lock for actuating the opening valve, means controlled by the lock for independently open- 40
- ing said valves, and means controlled by the lock for causing the valve to remain open until the door reaches the end of its movement. 45
7. The combination with a door and a pneumatic motor therefor, of an electrically actuated door opening valve, an electrically actuated door closing valve, a lock for the door, starting circuits for opening the respective valves, and maintaining circuits for holding the valves open, said maintaining circuits being controlled by the lock. 50
8. The combination with a door and a pneumatic motor therefor, of an electrically actuated door opening valve, an electrically actuated door closing valve, a lock for the door, starting circuits for opening the respective valves, maintaining circuits for holding the valves open, said maintaining circuits being controlled by the lock, and means movable with the door for alternately connecting a source of energy to the opening and closing circuits respectively. 55

In witness whereof I have hereunto set my hand this 13th day of August, 1915.

THOMAS FARMER, JR.
